UNITED STATES PATENT OFFICE

WILLIAM E. JOOST, OF OAKLAND, CALIFORNIA, ASSIGNOR TO ELECTRICAL PRODUCTS ASSOCIATES, OF LOS ANGELES, CALIFORNIA, A CORPORATION OF CALIFORNIA

NEON FLASH SIGN

Application filed September 19, 1932. Serial No. 633,698.

This invention is a neon flash sign and is especially directed to a neon sign in which the characters are built up in illumination to form the completed characters.

5 The usual method of flashing neon signs is to flash the entire characters at one time and complete. It is known that different characters have been consecutively flashed to form a series of completed characters, however, my invention is intended to build up the individual characters by consecutively flashing different portions to form a completed character.

An entirely new and unexpected result is obtained by this particular method of flashing the characters and creates in the mind of the observer, a certain curiosity during the building up of the character which is entirely different from that created by the 20 flashing of consecutive complete characters.

In addition to this, it provides a means of forming the different parts of the individual characters with differently colored illumination and thereby provides a means for producing some very artistic effects.

It is therefore the main object of this invention to provide a neon sign with characters, different portions of which are provided with differently colored illumination, and the different portions of which are successively flashed to provide a complete character.

Another object of the invention is to provide the neon sign with a series of characters, each of which characters are composed of a series of parts and each of which parts is provided with a different color of illumination.

Other objects and advantages of the invention will become apparent as the following description is read on the drawing forming a part of this specification and in which similar reference characters are used to indicate similar parts throughout the several views, 45 of which;

Fig. 1 is a plan view of the invention, and

Fig. 2 is a wiring diagram which is particularly adapted to the operation of the invention.

50 The invention consists of characters formed

of neon tubing, each character being formed of a plurality of sections and consists of a background or mounting plate 10, on which is mounted a character or a plurality of characters, each character being formed in a plurality of sections, and being indicated in the drawing as formed of three superposed sections 11, 12 and 13, each of the sections having terminals 14, 15 and 16 respectively.

The individual sections are connected throughout a series of characters, the intervening portions 17, 18 and 19 being covered with an opaque material so as to completely isolate the connections from the active portions of the characters, this practice being old in the art and not claimed.

In the operation of this device, circuit breaking and distributing means is required to successively flash the various sections of the characters and retain the sections in illuminated condition to build up the entire character, then suddenly interrupting the circuit to all sections of the characters, and for this purpose a rotor is provided with three commutator bars 20, 21 and 22, each of which is respectively connected to one terminal of the secondaries of three step-up transformers 23, 24 and 25, the other terminal of the transformers being respectively connected to one terminal or electrode of each of the neon tubes or character sections 17, 18 and 19, the other terminal or electrode of each tube being respectively connected to the brushes 26, 27 and 28, which brushes cooperate in line with the commutator bars or ring segments 20, 21 and 22.

The primaries of the transformers 23, 24 and 25, are respectively connected to a source of alternating current through the line wires 29 and 30.

In operation, brush 26 first comes in contact with the end 31 of commutator bar 20, illuminating the upper portion of the sign included between the terminals 14, and as the rotor rotates in the direction of the arrow, the end 32 of commutator bar 21 next cooperates with the brush 27, illuminating the tube included between the terminals 16 and after this period, three brushes are in contact with their respective commutator

bars and maintain all three sections of tubing under illuminating conditions until the rotor has reached the point shown on the drawing, after which a further slight movement of the rotor breaks contact between the brushes and the commutator bars, extinguishing all three sections of the sign simultaneously.

It will be noted that by this process the order through a series of characters may be reversed or changed, to give mixed effects, such as illuminating the upper section of the "G", the lower section of the "A", and the intermediate section of the "S" simultaneously instead of the entire upper section of all of the characters, and furthermore each section may be composed of a plurality of different colors and by stepping the position of the coincidently illuminated sections of the various characters, a great many different effects can be produced.

The process of forming a character in the form of a neon flash sign, the character being formed of a plurality of different colored portions has special advantages over any other form or method of flashing neon signs and very decisively attracts attention to the sign, due to both, the specific flashing sequence of the individual characters, and the colored combinations brought out during the flashing of the character, and the fact that the individual characters are composed of a plurality of different colors, in other words being vari-colored.

Having described an operative method and device, it will be understood that variations in construction and arrangement of parts which are consistent with the appended claims may be resorted to, without detracting from the spirit or scope of the invention, or sacrificing any of the advantages thereof;

I claim:—

1. An illuminated sign comprising a character divided into a plurality of sections, each section being formed of a length of neon gas filled tubing, and provided with individual terminals, an individual source of high tension current for each section, and means for successively making the circuits and simultaneously breaking the circuits to the sections.

2. An illuminated sign comprising a character divided into a plurality of sections, each section being formed of a length of neon gas filled tubing and provided with individual terminals, an individual source of high tension current for each section, and means for successively making the circuits and simultaneously breaking the circuits to the sections, and each section having incorporated in the neon gas a different light coloring medium, a vari-colored illuminated character being thereby produced in a series of steps and extinguished as a whole.

3. An illuminated neon sign comprising a plurality of characters, each character con-

sisting of a plurality of sections, each section consisting of an individually excited length of neon tubing, each section having a different colored illumination whereby continuity of the character as a whole is interrupted, and means for successively flashing the various sections whereby the effect of continuity is momentarily impressed on the eye of the observer.

In testimony whereof I affix my signature. 75
WILLIAM E. JOOST.
